(57) **CLAIM**

The ornamental design for a handguard for firearms, as shown and described.

DESCRIPTION

FIG. 1 is a top plan view of a handguard for firearms, showing my new design;

FIG. 2 is a front view of FIG. 1;

FIG. 3 is a front right-side perspective view of FIG. 1;

FIG. 4 is a left-side view of FIG. 1;

FIG. 5 is a right-side view of FIG. 1;

FIG. 6 is a bottom view of FIG. 1; and,

FIG. 7 is a rear-left-side perspective view of FIG. 1.

The broken line in the drawings depicts unclaimed portion of the handguard and the environment only and forms no part of the claimed design.

Present design is intended to be used as a handguard for a firearm.
